(57) **CLAIM**

The ornamental design for a camera, as shown and described.

DESCRIPTION

The patent and application file contain drawings executed in color. Copies of this patent or patent application publication with color drawings will be provided by the Office upon request and payment of the necessary fee.

FIG. 1 is a top front perspective view of a camera showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The dot-dash lines in the Figures and the area within the dot-dash lines depict portions of the camera in which the design is embodied and form no part of the claimed design.
